WASHING MACHINE DRIVE

John Oakley, Springfield, Mass., assignor to
 Perkins Machine and Gear Company, West
 Springfield, Mass., a corporation of Massachusetts

Application April 11, 1944, Serial No. 530,457

3 Claims. (Cl. 74—81)

This invention relates to improvements in washing machines and the like and is directed more particularly to driving mechanisms therefor.

The principal objects of the invention are directed to driving mechanism which is particularly adapted for washing machines and is characterized by frictionally engageable driving and driven members whereby a shaft for an agitator may be driven back and forth through various angles.

Mechanisms of the type to which this invention relates are intended to be responsive to the load applied to an oscillatable shaft, such as the agitator shaft, and are arranged for adjustment to accommodate or operate on materials and fabrics of various kinds.

Some materials require more or less agitation than others and to that end the novel construction of this invention makes it possible to accommodate the angle of oscillation of the shaft to the material or fabric being washed. That is, the angle of oscillation may be varied from zero to the maximum, even while the mechanism is in operation.

Various novel features and advantages of the invention will be observed from the following description of the invention in the form at present preferred.

In the drawing:

Fig. 1 is a partial inverted plan view of a washing machine tub having the novel features of the invention associated therewith;

Fig. 2 is a side elevational view of the driven member of the mechanism shown in Fig. 1;

Fig. 3 is a plan view showing the driving member in engagement with the driven member;

Fig. 4 is a plan view of the adjusting member of the mechanism; and

Fig. 5 is a sectional elevational view on the line 5—5 of Fig. 1.

Referring now to the drawing more in detail, the invention will be fully described.

A tub of a washing machine is represented by 2 to the bottom wall 4 of which is secured a housing 6 that may have a cover 8.

A drive shaft 10 is journalled in the housing and extends upwardly along the side of the tub for operating a wringer mechanism. A motor 12 supported by a bracket 14 has a shaft 16 connected by a coupling 18 to a shaft 20 that is journalled in the housing. A worm 22 on shaft 20 meshes with a gear 24 on shaft 16.

An agitator shaft 26 journalled in the housing 55 A collar 72 is provided on the rod 66 and a

extends up into the tub through wall 4. A driven member 30 is fixed on shaft 26.

A segment 32 is journalled on shaft 34 and it has a driving member 36 in the form of a curved bar secured thereto at one end while its other end may slide between lugs 38.

A link 40 has opposite ends pivoted at 42 and 44 to the members 24 and 32 so that as the member 24 rotates the member 32 swings back and forth. The driven and driving members 30 and 36 have inclined frictionally engageable faces so that the latter may be driven by the former. The driven member is shown as a female member but it may have a circumferential tongue with the driving member having a groove.

The curvature of the driving member 36 is preferably on a radius less or slightly less than the distance from the axis of the shaft 34 to the driving surfaces of said member 36. The said member 36 is somewhat yieldable particularly between its ends and the said shaft 34 is movable towards and away from the driven member 30.

This may be accomplished in various ways but in the form of the invention shown the shaft 34 has a part 40 that is oscillatable in the cover 8 which is eccentrically disposed relative to the part 34. By rotating the part 40 in one direction or the other the driving member 32 is moved towards and away from the driven member.

When the driving member 32 is moved away from the driven member 30 the driving member in its back and forth movements will not operate the driven member. As the said driving member is moved towards the driven member to engage the engageable surfaces the driven member is oscillated thereby.

The driving member 36 being yieldable the driving and driven members are therefore yieldingly and frictionally engageable so that with the curvature of the driving member being on the shorter radius, as described, the angle of oscillation of the driven member may be varied accordingly as the driving member is moved in and out.

* To move the shaft 40 for varying the angle of oscillation a lever 60 is secured to the said shaft which carries a member 62 that has an inclined face, as shown in Fig. 4.

An operating rod 64 has a lower portion 66 journalled in a bracket 68. The rod portion 66 extends through member 62 and has a member 70 thereon that is provided with a projection for acting on the inclined surface of member 62 as shown.

spring 74 on the said rod 66 acts to yieldingly hold the parts 62 and 70 in engagement.

A clutch 76 is slideable but non-rotatable on the rod 66 and it has teeth engageable in grooves of the member 68. A spring 78 on rod 66 between member 76 and a collar 80 on the rod urges the member 76 into engagement with the member 68.

By rotating rod 66 in one direction or the other the lever 60 is swung in one direction or the other thereby to move the shaft 34 towards and away from the driven member. In that way the angle of oscillation of the driven member may be varied. The engageable members 68 and 76 hold the rod 66 in adjusted positions.

While the driven member 30 is shown to be outside the driving member 36 it may be desired in some cases to locate the same inside of said member and in any event the driving and driven members may be arranged for the yielding frictional engagement whereby the angle of oscillation may be varied.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. Variable mechanism for a washing machine having an agitator shaft comprising in combination, a driven member on said shaft, a driving member oscillatable on an axis spaced from and

parallel to the axis of the agitator shaft, said driven member having angularly disposed friction faces, said driving member having a peripheral portion relatively yieldable intermediate opposite ends thereof provided with friction faces complementary to and engageable with the faces of the driven member, and said driving member movable towards and away from the driven member.

2. Variable mechanism for a washing machine having an agitator shaft comprising in combination, a driven member on said shaft having spaced relatively angularly disposed friction faces, a driving member oscillatable on an axis spaced from and parallel to the axis of the agitator shaft having a peripheral portion connected thereto at opposite ends being relatively yieldable intermediate said ends and provided with friction faces complementary to and engaging the faces of driven member, and means to move the driving member towards and away from the driven member.

3. Variable mechanism for a washing machine having an agitator shaft comprising in combination, a driven member on said shaft having spaced relatively angularly disposed friction faces, a driving member oscillatable on an axis spaced from and parallel to the axis of said agitator shaft having a curved peripheral portion provided with friction faces complementary to the friction faces of the driven member which are formed on a slightly less radius than the distance between the axis of oscillation of the driving member and friction faces of the driven member, said peripheral portion being relatively yieldable intermediate its ends, and means for moving the driving member towards and away from the driven member.

JOHN OAKLEY.
